JOINT STRUCTURES IN BILLFOLDS OR OTHER ARTICLES OF FLEXIBLE SHEET MATERIAL

John Harwood, Walsall, England

Application May 20, 1953, Serial No. 356,181

Claims priority, application Great Britain April 1, 1953

8 Claims. (Cl. 150—38)

This invention is concerned with bill-folds having a partitioned bill-receiving compartment formed of back and front members connected together along one adjacent longitudinal edge to form the bottom of the compartment, the lateral extremities of the compartment being closed in any suitable manner and which the other longitudinal edge forming the top of the compartment is open to permit the insertion and removal of bills, notes, or other papers, and the compartment having one or more internal partitions comprising pieces of sheet material of the kind specified extending between the lateral extremities of the compartment, and of sufficient depth to form effective separators for the bills, notes or other papers.

Hitherto, such partitions have normally been retained within the compartment at their lateral extremities and have sometimes been left free along their bottom edges or alternatively their bottom edges have been secured by stitching extending through the partition concerned and through one or both of the back and front members forming the compartment.

If the bottom edge of the partition is left free, then owing to the length of this member (which may be of the order of 9 inches) there is a tendency for it to be withdrawn from the compartment when taking out bills, notes or papers, and it then no longer provides effective separation so that these tend to become confused and crumpled. This effect is accentuated by the distortion or twisting of the partition which accompanies its displacement.

In the alternative construction, where the partition member or each of same is held in position along its bottom edge by stitching, such stitching reduces the effective depth of the compartment for a given depth of back and front members making it necessary to increase the depth of the latter for a given bill or note size, and further the stitching operation materially increases the complication and cost of manufacture.

The object of the present invention is to provide a new or improved construction in which the partition member or members are effectively retained in position without substantially increasing the complication and cost of manufacture.

Referring to the drawings:

Figure 1 is a perspective view of a bill-fold incorporating the features of the invention, the bill-fold being shown in an intermediate position between its extended or flat position and its folded position.

Figure 2 is a cross sectional view of the bill-fold on the line 2—2 of Figure 1.

Figure 3 is a fragmentary view on an enlarged scale showing the joint structure by means of which the partition member of the bill-fold compartment is secured to the bottom of this compartment.

Figure 4 is a fragmentary view showing the detailed construction and arrangement of a sub-pocket formed exteriorly of the main bill-receiving compartment on one of the outer members thereof.

2

Figure 5 is a cross sectional view on the line 5—5 of Figure 4 showing the joint structure involved in the construction of this pocket.

Figure 6 is a fragmentary view in plan and in cross section on the line 6—6 of Figure 1 showing the construction and arrangement of a sub-pocket of a gusseted type positioned similarly to that illustrated in Figure 4 but at the opposite lateral extremity of the bill-fold.

Figure 7 is a fragmentary view on an enlarged scale showing a suspension strap arrangement for supporting the partition member of the bill-fold compartment at its lateral extremities.

Figure 8 is a fragmentary view in plan and in section on the line 8—8 of Figure 4 illustrating an alternative manner of securing the end of a suspension strap.

Figure 9 is a view similar to Figure 8 illustrating yet another alternative manner of securing the end of a suspension strap and

Figure 10 is a view similar to Figure 7 but illustrating an alternative suspension strap arrangement.

In the construction illustrated, the bill-fold has a bill or note receiving compartment indicated generally at 10 defined by outer members hereinafter referred to for convenience as a back member 11 and a front member 12 of any convenient configuration such as the elongated, rectangular form illustrated, the back member being somewhat deeper than the front member so that the upper margins of the bills or notes placed in the compartment 10 are exposed for convenience in extracting these when required.

The back member 11 comprises a central or main portion 13 of a length at least equal to the length of the notes or bills which it is required to accommodate in the compartment 10 and the lateral extremities of this main portion 13 are connected, preferably integrally with lateral flaps 14 and 15 foldable about respective folded lines 16 and 17 coincident with the lateral extremities of the compartment and extending transversely to the length thereof as seen particularly in Figures 1 and 4.

For the purpose of convenience in the following description and not in any limiting sense the bill-fold will be considered to occupy an upright position, that is to say, it will be considered as disposed in a vertical plane with the mouth of the compartment 10 uppermost as illustrated in Figure 1.

The front member 12 of this compartment may be integrally connected with the back member through a fold-line as indicated at 18 (Figures 2, 4 and 5) extending along their common bottom edges and the front member 12 may be of complex form part thereof which is united integrally with the back member comprising two separate panels 19 and 20 of approximately rectangular form spaced apart longitudinally so as to afford between them a somewhat narrower gap or cut-out as indicated at 21.

This gap or cut-out does not extend completely to the bottom fold-line 18 and may terminate at a distance from this fold-line, for example, of $\frac{1}{8}$ " or thereabouts, the lower edge of this gap or cut-out having a tab preferably integrally therewith extending upwardly for a short distance, for example, from $\frac{1}{2}$ " to $\frac{3}{4}$ " or thereabouts. The tab which is indicated at 22 (Figures 2 and 3) by its presence enables the fold-line forming the bottom edge of both front and back members to be free from cuts or discontinuities in the central region adjacent to the gap or cut-out 21. Further, this tab as hereinafter described, may be utilised for the purpose of retaining a partition member in the compartment 10.

Each of the panels 19 and 20 of the front member may be folded over at its upper edge in a direction inwardly of the compartment, the folded-over margin for

the panel 20 being indicated at 23 (Figure 2) and for the panel 19 is visible at 24 (Figure 7).

These folded-over margins 23 and 24 may as indicated in Figure 7 be cut or slit longitudinally to provide at each end of the compartment 10 a suspension strap 25 or alternatively as seen in Figure 10, these folded-over margins may have secured thereto a structurally separate suspension strap 26 which may be threaded through longitudinally spaced slits in the folded-over margin 24 situated inwardly of the lateral extremities thereof, one of these slits being indicated at 27 (Figure 10).

Internally of the compartment 10 is provided a partition member 28 which may be a depth intermediate between the depth of the back and front members 11 and 12 and which may comprise an elongated rectangular-shaped piece of sheet material of the kind specified having openings preferably in the form of slits as indicated at 28a, Figures 7 and 10, inset a short distance from its lateral extremities through which the suspension straps 25 or 26 are passed.

The front member of the compartment may incorporate an additional separate sheet 29 which in combination with the two panels 19 and 20 forms main front pockets as indicated by the space 52 (Figure 2) in the case of the panel 20 access to these main front pockets being obtainable at respective opposite edges 53 and 54 of the central cut-out between the panels 19 and 20.

This sheet 29 is held in position partly by reason of the fact that it lies beneath the folded-over margins 23 and 24 of the panels 19 and 20 and partly by the provision of slits or openings inset for a short distance from its lateral extremities as indicated at 30 Figures 8 and 9 to enable the suspension straps to pass through it and perform a like function to that in which they perform for the partition member 28.

The outer or free ends of the suspension straps may have a peripheral configuration defining a head portion 31 and these headed portions may be secured adhesively to the exterior face of the appropriate panel 19 or 20 as seen particularly in Figures 4, 7, and 8 by passage of the suspension straps through slits 32 in the panels, the length of these slits being less than the corresponding dimensions of the head portion measured in the vertical direction so that the strap is retained not only by the adhesive but positively by abutment of the head against the material of the panels above and below the ends of slits 32.

In the alternative arrangement illustrated in Figure 8, the end of suspension strap designated 25 for convenience but which may be of the form indicated in Figure 8 is separated into component plies 55 and 56 the one 55 of which is passed through the opening or slit 32 in the panel member 19 to lie against its front face and the other 56 of which is secured to the rear face of this panel member.

In yet another alternative as shown in Figure 9 both the plies 55 and 56 may be passed through the opening or slit 32 and splayed apart to extend in opposite directions, these plies being adhesively secured to the front face of the panel member 19 on opposite sides of the opening or slit 32.

A particular advantage of this arrangement for securing the partition and loose lining member in position is that since the suspension straps may be formed as shown in Figure 10 by an integral part of the folded-over margins of the panel members, their provision does not involve an extra thickness of material. Moreover, the manner of securing of these straps by passing them through slits in the panels and adhesively securing the heads avoids any doubling of the thickness of the suspension straps throughout their lengths and secondly both these factors are contributory to avoiding any undesirable protuberances or multiplicity of thicknesses locally in the region where the partition member is supported

by these straps and in the region where the straps themselves are secured.

With the composite front member 12 folded about the lower fold-line 18 face to face with the back member 11 to define the compartment 10 which is sub-divided by the partition member 28, the flaps 14 and 15 are then folded over the exposed faces of panels 19 and 20 respectively, and secured in position in conjunction with other components to form sub-pockets as hereinafter described.

For retaining the partition member 28 in position in the compartment 10 at its central region the bill-fold incorporates a joint structure involving the lower edge portion of the partition member and the tab 22.

The primary step in effecting this joint structure is to form one of the pieces, in this case the partition member 28, at its lower edge portion of at least a pair of plies 33 and 34 which could be separate sheets of material adhesively or otherwise secured together at locations other

than that at which the joint is to be effected but which are preferably each united integrally with the main body portion of the piece of partition member 28 which except for the plies is of homogeneous unlaminated form. In such a homogeneous or laminated sheet of material whether of leather or the other sheet materials of the kind specified the plies may be formed by a "skivering" or "pairing" of the material for the required distance inwardly from the edge thereof in this case the bottom edge 35, the terms "skivering" or "pairing" being understood in the art as meaning a cutting or splitting of the sheet in a plane parallel to and intermediate the faces of the sheet so as to produce the separate plies.

The other piece of material, in this case the tab 22, is inserted between the plies 33 and 34 which are temporarily separated or left unbonded to each other in the area in which the inserted portion is to be accommodated and then afterwards united together and to one or both faces of the inserted portion by a suitable adhesive.

The inserted portion or tab 22 may enter between the plies 33 and 34 where these are formed by "skivering" or "pairing" or where these are inherently present by the use of a laminated sheet at the edge in this case the edge 35.

Preferably, however, as illustrated one of the plies 34 may have an opening such as a slit 36 inset from the edge adjacent to which the piece or tab 22 is to lie and this piece or tab may enter between the plies through this opening or slit 36.

A further feature of the joint structure which may advantageously be incorporated whether the inserted portion enters through a slit or opening or at the edge of the plies is that the inserted portion or tab 22 may have a peripheral profile of a form to present a relatively narrow connecting neck 37 uniting a head 38 to the main body of the member associated with the tab in this case the front member 12. The head may have abutments or shoulders 39. These shoulders 39 engage with an edge of the slit or opening in the regions at the ends thereof as seen in Figure 3 so as to resist in combination with the adhesive any withdrawal of the inserted piece or tab.

It will be apparent that the manner in which the partition member is secured at its bottom edge permits bills, notes or other papers to be inserted into the subdivisions 40 and 41 of the compartment 10 to the whole depth thereof without any obstruction being afforded to such insertion and without any part of the bottoms of these sub-divisions being effectively lost for bill or note accommodation purposes by virtue of the retaining means for the partition member.

The sub-pockets formed on the exposed faces of the panels 19 and 20 of the front member of the bill-fold each incorporate a further joint structure.

At the left-hand end of the bill-fold as viewed in Figure 1, the sub-pocket is formed partly by the panel 19

itself which constitutes a base member or backing for the pocket and the pouch portion for the pocket is formed of a strip of flexible sheet material of the kind specified as indicated at 42 (Figures 4 and 5).

The peripheral margins of this strip 42 in the particular case in question extending along the upper and lower edge thereof are formed of separated plies 43 which are splayed apart as seen particularly in Figure 5 so that they extend in opposite directions from each other.

Each of the peripheral margins incorporating these splayed plies are passed through openings preferably in the form of slits 44 in the panel, there being two such openings arranged parallel to each other and spaced apart at the requisite distance, such openings lying adjacent to the upper and lower edges of the panel respectively.

The plies 43 are secured in contiguous relationship with the inner face of the panel 19 by a suitable adhesive and it will thus be observed that the upper and lower boundaries of the pocket are thus completely sealed so that there is no possibility of the contents of the pocket passing there from into the interior of the compartment 10.

It would be possible to form the strip 42 on separate sheets of material of which the marginal portions are splayed apart whilst in the main body portion they are adhesively secured together but preferably each of the plies 43 is integrally connected with the main body portion which is of homogeneous or unlaminated form. In this case, the plies may be formed by a "skiving" or "pairing" operation as previously described.

The bottom of the pocket formed by the outer lateral extremity 45 of the piece 42 is closed by the flap 14 to the extremity of which is preferably secured by adhesive a relatively stiff card or sheet 46 of paper or the like material which is inserted into the open mouth 47 of the sub-pocket and secured adhesively to the interior face of the strip 42. In a preferred arrangement the end of the flap 14 is formed with a tab having a headed profile as indicated in chain dotted lines 57 affording a pair of laterally directed ears 58 and connected to the main body of the flap 14 through a narrower neck portion 59. The card 46 has a slit of a width intermediate that of the neck portion 59 and that between the extremities of the ears 58 (and coincident with junction line 60) so that when the tab is passed through this slit and adhesively secured against the underside of the card and the whole is adhesively secured to the interior face of the piece 42 the flap is positively retained in position by the abutment of the ears 58 against the inner face of the card to augment the securing effected by the adhesive.

At the right-hand end of the bill-fold the panel 20 is provided with a somewhat more capacious pocket of gusseted construction, the formation of which can best be seen in Figures 1 and 6. In this construction the front and side members of the sub-pocket may be formed of a piece of flexible sheet material of the kind specified in the shape of a trapezium the marginal portions of this piece adjacent to the non-parallel sides being pleated inwardly to form inwardly directed V-shaped gussets 48, the main body of this piece which connects these marginal portions not being visible in Figure 1 by virtue of its extending beneath the flap 15.

The edges of the gussets 48 which are adjacent to the panel 20 may be formed into separated plies in the manner illustrated for the sub-pocket at the other end of the bill-fold and may be passed through openings or slits adjacent to the upper and lower edges of the panel 20, as indicated at 49, these plies then being splayed apart and secured adhesively to the interior face of this panel in a manner analogous to that illustrated in Figure 5.

The flap 15 forms a closure member for the bottom of this sub-pocket the mouth of which may be provided with a flap 50 secured to the panel 20 by a joint structure similar to that used for the gussets 48 and the strip 42

of the other sub-pocket. As seen in Figure 6 the inner extremity of this flap is formed in separated plies 51 which are passed through a suitable opening or slit in the panel 20 and are adhesively secured to the interior surface of this adjacent to the slit or opening.

A bill-fold constructed as above described may be held together in its finished form entirely with the aid of folding joint structures and adhesive arranged to secure the component parts permanently or releasably together without the necessity for any stitching operations and the whole article may thus be manufactured at relatively low cost without involving the degree of skill normally attendant upon the carrying out of stitching or sewing operations.

Further, the partition member 28 by virtue of the suspension straps has a limited degree of endwise float enabling it to accommodate itself to the contents of the compartment 10 when the bill-fold is in its closed or folded position whilst the central anchorage provided by the tab 22 effectively prevents any tendency to pull the partition member out and distort it when withdrawing bills, notes or other papers from the sub-divisions 40 and 41.

What I claim then is:

1. In a bill fold formed of flexible sheet material of the general class specified, the provision of a bill receiving compartment formed of back and front members connected together integrally with each other along a fold line forming the bottom of the compartment, one of said members being cut transversely to the fold line and adjacent thereto to provide an upwardly extending tab having its lower extremity situated close to but above said fold line so that the latter presents a continuous folded edge free from cuts or discontinuities, and a partition member in said compartment connected at its lower edge with said tab.
2. In a bill fold formed of flexible sheet material of the general class specified, having a bill receiving compartment formed of back and front members connected together along one adjacent longitudinal edge to form the bottom of the compartment; the provision of a partition member in said compartment, an upwardly extending tab situated in said compartment in a region lying centrally between the lateral extremities of said compartment, said tab being anchored at its lower end by connection to said back and front members at said longitudinal edge, said tab having a peripheral profile of a form presenting a head and a relatively narrow connecting neck, said partition member having a lower edge portion comprising a pair of plies, and said tab head being disposed between said plies and secured in position by adhesive applied between contiguous faces of the plies beneath and within the lateral confines of said head.
3. In a bill fold formed of flexible sheet material of the general class specified, having a bill receiving compartment formed of back and front members connected together along one adjacent longitudinal edge to form the bottom of the compartment; the provision of a partition member in said compartment, an upwardly extending tab situated in said compartment in a region lying centrally between the lateral extremities of said compartment, said tab being anchored at its lower end by connection to said back and front members at said longitudinal edge, said partition member having a lower edge portion comprising a pair of plies one of which has a slit inset from the lower edge of the plie, said tab having a peripheral profile of a form presenting a head and a relatively narrow neck, said head being disposed between said plies with said neck emerging from said slit, said head being wider than the length of said slit and secured in position between said plies by adhesive applied between contiguous faces of said head and said plies.
4. In a bill fold formed of flexible sheet material of the general class specified, having a bill receiving com-

partment formed of back and front members connected together integrally with each other along a fold line forming the bottom of the compartment; the provision of a partition member in said compartment, an upwardly extending tab situated in said compartment in a region lying centrally between the lateral extremities of said compartment, said tab being anchored at its lower end by integral connection with said front member at a position close to but above said fold line so that the latter presents a continuous folded edge free from cut-outs or discontinuities, said partition member having a lower edge portion comprising two plies each united integrally with the remainder of said partition member which is of homogeneous unlaminated form, said tab being disposed between said plies and secured in position by adhesive applied between contiguous faces of said tab and said plies to retain the partition member centrally of its length against upward displacement.

5. In a bill fold of flexible sheet material of the general class specified, having a bill receiving compartment formed of back and front members connected together along one adjacent longitudinal to form the bottom of the compartment; the provision of a partition member in said compartment, an upwardly extending tab in said compartment connected at its lower end with said longitudinal edge and with said partition member to retain the latter centrally of its length against upward displacement, suspension straps disposed near opposite lateral extremities of said partition member and having their lengths extending at least approximately parallel to the bottom of the compartment, opposite ends of each suspension strap being connected to said front member, and a portion of each suspension strap intermediate its ends passing through a slit in the adjacent lateral margin of said partition member.

6. In a bill fold formed of flexible sheet material of the general class specified, the provision of a bill receiving compartment formed of back and front members connected together integrally with each other along a fold line forming the bottom of the compartment, said front member comprising panels on opposite sides of the centre of said fold line, adjacent inner edges of these panels being spaced apart from each other and the upper margins of said panels being folded over into the interior of said compartment, said front member further comprising a separate sheet extending for the length of said compartment and inserted behind said panels so as to be enclosed along its upper margin between said panels and said folded over upper margins, the latter being slit parallel to their upper edges and adjacent to their lateral extremities to provide suspension straps at each of the lat-

eral extremities of said compartment, said suspension straps being secured at their outer ends to said inserted piece, a partition member in said compartment having a lower edge portion comprising a pair of plies, an upwardly extending tab in said compartment, said tab being integrally connected at its lower end with said front member of the compartment at a position between the spaced inner edges of said panels, said tab being disposed between the plies of said partition member and secured in position by adhesive applied between contiguous faces of the tab and the plies to retain the partition member centrally of its length against upward displacement, said partition member adjacent its lateral extremities having slits through which suspension straps are passed to secure it against upward displacement at these positions.

7. In a bill-fold formed of flexible sheet material of the general class specified, having a bill-receiving compartment formed of back and front members connected together along one adjacent longitudinal edge to form the bottom of the compartment; the provision of a partition member in said compartment, an upwardly extending tab in said compartment connected at its lower end with said longitudinal edge and united with the partition member.

8. In a bill-fold of flexible sheet material of the general class specified, having a bill-receiving compartment formed of back and front members connected together along one adjacent longitudinal edge to form the bottom of the compartment; the provision of a partition member in said compartment, an upwardly extending tab situated in said compartment in a region lying centrally between the lateral extremities of said compartment, said tab being anchored at its lower end by connection to said back and front members at said longitudinal edge, said partition member having a lower edge portion comprising a pair of plies, and said tab being disposed between said plies and secured in position by adhesive applied between contiguous faces of the tab and the plies to retain said partition member centrally of its length against upward displacement.
